UNITED STATES PATENT OFFICE

JOHN F. CROWLEY, OF LYNN, MASSACHUSETTS, ASSIGNOR TO UNITED SHOE MACHINERY CORPORATION, OF PATERSON, NEW JERSEY, A CORPORATION OF NEW JERSEY

ART OF MANUFACTURING SHOES

Application filed March 9, 1929. Serial No. 345,823.

This invention relates to improvements in the art of manufacturing shoes. The invention is herein illustrated in its application to McKay-sewed shoes but in certain of its aspects it is useful also in connection with the making of other types of shoes wherein the shank stiffener is located between inner and outer soles as, for example, in welt shoes.

In a co-pending application filed concurrently herewith in the name of A. W. Matthews, Serial No. 345,822, there is disclosed a method of making shoes in accordance with which a shank stiffener is secured at its forward end to both the inner and outer soles of a shoe by means of a two-part fastener consisting of an eyelet, which extends through the shank stiffener and the insole, and a tubular rivet which extends through the outsole and through the eyelet.

One object of the present invention is still further to improve and simplify the method above referred to and with this object in view a novel and practicable method has been provided in the practice of which a shank stiffener is firmly and permanently secured to both the inner and outer soles by the employment of only a single unitary fastener or a plurality of unitary fasteners. In accordance with this novel method as herein exemplified, a shank stiffener having a rivet-receiving hole therein is secured to the insole of a shoe and located in predetermined relation to the shoe, a hole-forming tool, such as a drill or a punch, is inserted in the hole in the shank stiffener and thereby located relatively to the insole of the shoe after which the tool is operated to form a hole in the insole registering with the hole in the stiffener, an outsole is laid, and a unitary fastener, in the form of a tubular rivet, is passed inwardly through the outsole and through the registering holes in the shank stiffener and the insole, the rivet making the hole through which it passes in the outsole and the inner end of the rivet being clenched against the inner surface of the insole so as permanently to secure together the shank stiffener and the inner and outer soles. As herein illustrated, the shank stiffener is provided with two rivet-receiving holes, one located in its for-

ward portion and the other at or near the middle of the stiffener, and a rivet is employed in each of the holes for securing the stiffener in place.

The invention will be explained with reference to the accompanying drawings, in which

Fig. 1 is a perspective view of a McKay-sewed shoe in process of manufacture, showing the shoe as it appears after the shank stiffener has been applied to the insole but before the outsole has been laid;

Fig. 2 is a longitudinal sectional view of the shoe shown in Fig. 1, illustrating the manner of forming the rivet-receiving holes in the insole;

Fig. 3 is a longitudinal sectional view of the shoe as it appears after the outsole has been attached to the shoe, this figure illustrating particularly the manner of inserting the rivets;

Fig. 4 is a transverse sectional view of the shoe shown in Fig. 3, the section being taken through one of the shank stiffener attaching rivets; and

Fig. 5 is a perspective view of a completed shoe made in accordance with the present method.

In making a McKay-sewed shoe as herein illustrated an insole 10 is secured to a last 12 having the usual metallic bottom plate 14 (Fig. 2), the insole being attached by means of tacks 16 which are driven through holes 18 in the bottom plate 14. Thereafter an upper 20 is lasted over the insole and secured to the latter by lasting tacks 22 in the usual manner. A shank stiffener 24 is attached to the insole 10 preferably after the upper has been lasted over. The shank stiffener 24, which is preferably made of tempered steel, is curved longitudinally to correspond to the longitudinal curvature of the shank portion of the bottom of the last 12 and the illustrated stiffener is also arched somewhat transversely for the purpose of stiffening it. At each end of the stiffener is formed a tack hole 25 and as herein shown the stiffener is provided with two rivet-receiving holes 28 which were preliminarily formed in the stiffener, one in the forward

portion thereof and the other at or near the middle of the stiffener. After being properly located upon the insole, between the last-ed-over margins of the upper as shown in Fig. 1, the stiffener 24 is preliminarily attached thereto by driving tacks 26 through the insole, the points of the tacks engaging the metallic bottom plate 14 of the last and being turned over thereby and clenched against the inside surface of the insole.

Rivet-receiving holes 30 are thereafter formed in the insole 10 by means of a suitable tool such as the illustrated drill 32 (Fig. 2). The drill 32 is first projected through one of the holes 28 in the shank stiffener and thus located properly for the making of a hole in the insole after which the drill is driven downwardly into engagement with the bottom plate 14, thus making a hole in the insole registering with the hole in the shank stiffener. As herein illustrated the drill 32 is operated through each of the holes 22 in the stiffener for the purpose of making two holes 30 in the insole as shown in Fig. 2.

After the holes 30 have been drilled in the insole, an outsole 34 is laid in the usual manner and, either before or after the outsole has been secured by stitching to the upper, the shank stiffener is secured to both the inner 30 and outer soles by means of tubular rivets, such as the tubular rivets 36 (Figs. 3 to 5). Preferably, as shown in Fig. 3, the rivets employed are of the type having an entering end portion beveled to enable the rivet to force its way through stock in which no hole has preliminarily been formed to receive the rivet. As shown in Fig. 3, the bevel is formed at the outside of the rivet, thus insuring that the rivet will fit tightly within the hole which it forms in the outsole and furthermore facilitating the entrance of the rivet into the registering holes in the shank stiffener and in the insole. If desired, however, a rivet-receiving hole may be preliminarily formed in the outsole by means of a drill or punch inserted through the alined holes in the insole and shank stiffener from the inside of the shoe.

As illustrated, the rivets 36 are driven by means of the rivet-applying device shown in Fig. 3 which comprises a rivet-driving plunger 38, a rivet-setting anvil 40, a positioning pin 42 carried by the anvil 40, and means such as spring fingers 44 for holding a rivet beneath the plunger 38 in position to be driven. The positioning pin 42, as shown, projects centrally through the cupped upper end of the anvil 40 and is normally supported in operative position by means of a spring 46 located within the anvil and arranged to permit the pin 42 to be displaced downwardly by the rivet as the latter is forced through the holes in the shank stiffener and insole.

In operating the illustrated rivet-applying device, a shoe is positioned, as shown in Fig.

3, with the positioning pin 42 engaging within one of the holes 30 in the insole, thereby positioning the shoe relatively to a rivet which is held in position beneath the driving plunger 38 so that the rivet is coaxially alined with the holes in the insole and shank stiffener through which the rivet is to be driven. The plunger 38 is then operated to drive the rivet. As the rivet is driven it cuts its way inwardly through the outsole and passes through the alined holes in the shank stiffener and insole and finally the inner end of the rivet is turned outwardly by the cupped surface of the anvil 40 and clenched against the inside of the insole. This operation is repeated for the purpose of driving the two rivets 36, shown in Fig. 5. The two rivets 36 firmly and permanently secure the shank stiffener to both the inner and outer soles of the shoe in such a manner that the shank stiffener effectively stiffens the shank of the shoe so that it cannot become flattened or laterally twisted. The heads of the rivets 36 are set substantially flush with the outer surface of the outsole so that they do not detract from the appearance of the shoe. Inasmuch as the rivets fit tightly within the insole there is no opportunity for moisture to gain admission to the inside of the shoe through the holes occupied by the rivets.

Having described my invention, what I claim as new and desire to secure by Letters Patent of the United States is:

1. That improvement in the manufacture of shoes which consists in securing an insole to an upper, thereafter securing to the insole a shank stiffener having a fastener-receiving hole therein, inserting a hole forming tool in the hole in the shank stiffener and operating the tool to form a hole in the insole registering with the hole in the stiffener, laying an outsole, and passing a unitary fastener through the outsole and through the registering holes in the shank stiffener and the insole to secure together the outsole, the insole, and the shank stiffener.

2. That improvement in methods of manufacturing shoes which consists in securing an insole to a last, lasting an upper and securing it to the insole, securing to the insole a shank stiffener having a fastener-receiving hole therein, drilling inwardly through the hole in the shank stiffener and against the bottom of the last to form a fastener-receiving hole in the insole registering with the hole in the shank stiffener, laying an outsole and securing it to the upper, pulling the last, and passing a fastener through the outsole, and through the registering holes in the shank stiffener and insole to secure the shank stiffener to both the insole and the outsole.

3. That improvement in methods of manufacturing shoes which consists in securing an insole to a last, lasting an upper and securing it to the insole, securing to the insole a shank

stiffener having a fastener-receiving hole therein, drilling inwardly through the hole in the shank stiffener and against the bottom of the last to form a fastener-receiving hole in the insole registering with the hole in the shank stiffener, laying an outsole and securing it to the upper, pulling the last, utilizing the hole in the insole to locate the shoe relatively to cooperating members of a rivet-setting device with said hole in co-axial alignment with said members, and operating said device to drive a rivet inwardly through the outsole and through the aperture in the shank stiffener and the insole and to set the rivet thereby securing together the outsole, the insole, and the shank stiffener.

4. That improvement in the manufacture of shoes which consists in securing an insole to a last having a metal bottom, lasting an upper and securing it to an insole, locating within the space between the lasted-over margins of the upper and attaching to the insole a shank stiffener having a plurality of rivet-receiving holes therein, drilling inwardly through the holes in the stiffener and against the metal bottom of the last to form rivet-receiving holes in the insole located in predetermined relation to the shoe and respectively registering with the holes in the shank stiffener, laying an outsole and securing it to the upper and the insole, pulling the last from the shoe, and passing rivets inwardly through the outsole and through the registering holes in the shank stiffener and insole to secure the stiffener to both the insole and the outsole.

In testimony whereof I have signed my name to this specification.

JOHN F. CROWLEY.
